UNITED STATES PATENT OFFICE.

DANIEL MAHER, OF LIVERPOOL, ENGLAND.

DEVICE FOR PLAYING AND PRACTISING GOLF, PUTTING, AND OTHER GAMES.

1,135,706.

Specification of Letters Patent. Patented Apr. 13, 1915.

Application filed March 28, 1914. Serial No. 827,970.

To all whom it may concern:

Be it known that I, DANIEL MAHER, a subject of the King of Great Britain, residing at Liverpool, in the county of Lancaster, in the Kingdom of England, have invented certain new and useful Improvements in Devices for playing and Practising Golf, Putting, and other Games, of which the following is a specification.

This invention has for its object an appliance for catching balls in playing or practising golf, putting and other games.

It has been more especially designed for use in connection with putting indoors also a substitute for the usual holes that are made in the turf or lawns or putting greens into which a player seeks to drive his ball with the fewest strokes.

Such appliance comprises an exterior ring or base piece adapted to lie flat on the floor or ground, and a flange or lip projecting upward from the inner edge thereof so as to form a cup or receptacle for the ball, the flange being of such material that it will give inward when a ball impacts against it from the outside (so that the ball can freely enter the receptacle), but offer more resistance to the ball escaping therefrom.

My invention differs from known devices of this character, in that an upwardly extending flange or inwardly sloping flange has an annular base around the outside, which base forms a stand for the appliance to rest on, the flange being of thin pliable but resilient material so as to have insufficient rigidity to support the ball. When a ball rolls over the external base the portion of the flange against which the ball impacts, will be depressed or flattened inward, the resiliency of the flange causing it to resume its normal shape as soon as the ball has passed off therefrom.

The invention will be understood from the following description, reference being had to the accompanying drawings, in which,

Figure 1 is a perspective view of the appliance embodying my improvement, Fig. 2 a similar view with a ball shown in the act of entering it, and Fig. 3 a cross sectional view.

Referring to these figures, A is the annular ring or base piece, adapted to lie flat on the floor or ground. This base piece is of india rubber or any other suitable material, and around the inside edge thereof, a flange or rim B extends upward, so that

the base piece and flange in combination, form a cup or receptacle for a ball or balls. This flange B preferably slopes inward at a suitable angle, but it may be upright if desired, and it is made of india rubber so as to be resilient, and give inward from the outside pressure of a ball striking against it, so that the ball shall freely enter the receptacle. On the other hand the flange B offers more resistance to the ball escaping from the receptacle than it does to the ball entering it, but at the same time does not offer an absolute resistance to the escape of the ball, so that if the ball is hit too hard, it will, even though it enter the receptacle, come out again. The annular base A forms the double purpose as a stand for the appliance to rest on the floor or ground, and as a lead for the ball, before impacting against the flange B and rolling into the receptacle. By means of this external annular base A, the flange B will offer less resistance to the ball entering the receptacle, because a ball will deflect or flatten down that part of the flange against which it impacts. If the base was a disk instead of an annular ring, there would be two thicknesses of material for the ball to mount before it could enter the receptacle, viz. the thickness of the disk, and the thickness of the flattened down flange.

In use the player drives his ball by means of the usual club, and the ball on impacting against the external surface of the slanting side B flattens the same at the point of impact, as shown in Fig. 2, thus entering the receptacle. The side being resilient immediately springs back again, and the escape of the ball from the receptacle is resisted to a certain extent. There is little or no resistance to the ball entering the receptacle, owing to the facility with which the flange yields inward, and to the fact that it is flattened flush with the annular base, at the part where the ball strikes it.

The base piece A and flange B are by preference made in one of india rubber or other suitable material, or if desired they are formed separately, but solutioned or vulcanized together. If preferred, however, the base piece A might be of one substance and the flange B of another, fastened together in any suitable way.

I declare that what I claim is:

1. An appliance for catching balls in playing or practising golf, putting or other

games, comprising an annular base piece, and a flange or rim formed of a single thickness of thin pliable but resilient material extending upward from the inner edge of the base piece, the flange having insufficient rigidity to support the ball, whereby when a golf ball rolls over the external base, the portion of the flange against which the ball impacts, will be depressed or flattened inward, the resiliency of the flange causing it to resume its normal shape as soon as the ball has passed off therefrom.

2. An appliance for catching balls in playing or practising golf, putting or other games, comprising an annular base piece resting flat upon the ground or other surface and having a thin pliable and resilient upwardly and inwardly extending flange

formed of a single piece of material within the outer edge of said base piece, said flange having insufficient rigidity to support the ball, whereby when a golf ball rolls over the external base, the portion of the flange against which the ball impacts will be depressed or flattened inward, the resiliency of the flange causing it to resume its normal shape as soon as the ball has passed off therefrom. 20

In witness whereof, I have hereunto signed my name this 18th day of March 1914, in 30 the presence of two subscribing witnesses.

DANIEL MAHER.
